UNITED STATES PATENT OFFICE.

LOUIS GOLDSSTONE, OF ROCHESTER, NEW YORK.

BOOT OR SHOE COUNTER REINFORCE

1,277,713.

Specification of Letters Patent. Patented Sept. 3, 1918.

Application filed January 14, 1918. Serial No. 211,715.

To all whom it may concern:

Be it known that I, LOUIS GOLDSSTONE, of Rochester, in the county of Monroe and State of New York, have invented certain new and useful Improvements in Boot or Shoe Counter Reinforces; and I do hereby declare the following to be a full, clear, and exact description of the same, reference being had to the accompanying drawings, forming a part of this specification, and to the reference-numerals marked thereon.

This invention relates to a reinforce for boot or shoe counters and has for its more special object to permanently prevent curling of the counter or quarter upward from the margin of the affixed shoe heel should the shoe shrink in use by reason of alternate wettings and dryings, and thereby avoid the gaping joint ordinarily formed between a curled counter and the shoe heel. Such a gaping joint permits entrance of quickly destructive moisture and dirt to interior heel portions of the shoe, and also presents an unsightly appearance, both of which disadvantages are entirely obviated by this simple, inexpensive and efficient invention.

A preferred embodiment of the invention is sufficiently illustrated in the accompanying drawings in which similar reference characters indicate corresponding parts in all the figures.

Figure 1 is a side elevation of a woman's boot or shoe embodying this invention and with its quarter and heel portions broken away and in section.

Fig. 2 is an enlarged vertical transverse section taken on the line *a—a* in Fig. 1.

Fig. 3 is a top perspective view of a preferred form of the counter reinforce, removed from the shoe; and

Fig. 4 is a detail transverse section illustrating by contrast the common gaping joint between a shrunken counter or quarter and the margin of the affixed shoe heel.

In the drawings the numeral 1 indicates the counter reinforce which preferably has at its opposite side and rear marginal portions an upwardly projecting flange 2 formed preferably by cutting and pressing between dies any sufficiently strong and rigid plate substance of which the reinforce may be made. Indurated fiber has in practice proved satisfactory because it combines lightness with sufficient rigidity and strength and also may be readily pierced anywhere by the lasting and heel fastening

nails, but any other suitable material may be employed.

The counter reinforcing plate 1—2 is applied in a preferred manner inside of the inbent lasted portions of the shoe lining 3, and between the shoe insole 4, and the rearwardly extending narrow edge chamfered tongue portion 5 of the shoe outsole 6, and inturned lasted portions 7 and 8, respectively, of the shoe counter 9 and quarter 10. The lasting nails 11 pass inwardly through the parts 8, 7, of the shoe quarter and counter, the lining 3, if used, the main body or plate portion 1 of the counter reinforce, and the insole 4, and the fastening nails 12 pass inwardly through the outsole tongue 5 and the reinforce plate 1 and the insole 4, and all of the nails 11, 12, are clenched upon the inner face of the insole. The longer nails 13, which fasten the shoe heel 14 upon the outsole tongue 5 and closely against the inlasted portion 8, of the counter 10, are driven outwardly through the insole 4, and the outsole tongue 5 into the heel. The clenched inner ends of the nails 11, 12, and the heads of the nails 13 are all preferably covered by a leather, felt, or other suitable inner sole lining 15, as shown in Figs. 1 and 2 of the drawings.

It will be specially noticed that the rigid counter reinforce plate portion 1 prevents upward curling of the shoe quarter 8 and counter 9 away from marginal portions of the shoe heel 14 by shrinkage due to alternate wettings and dryings, and therefore the original close joint shown in Figs. 1 and 2, between the inbent lasted portion 8 of the shoe quarter 10 and the upper marginal portion of the affixed heel 14, will be permanently maintained in any boot or shoe to which this improved counter reinforce has been applied. This effect would be assured if the counter reinforce comprised only a substantially flat plate 1, not having the upturned marginal flange 2, but said flange materially strengthens the plate portion 1, and also gives a most desirable lateral support to lower rear portions of the shoe counter 9, and quarter 10, next the affixed heel 14, and therefore the marginally flanged counter reinforce 1—2 is preferred in practice.

Contrasting Fig. 4 of the drawings, wherein the counter reinforce 1—2 is omitted, shows the shrunken shoe quarter portion 8 and counter portion 7, curled upward from the margin of the affixed heel 14, thereby

producing at the heel joint a more or less wide gap 16, into which moisture and dirt may enter to injure inner heel portions of the shoe, and this gaping joint also presents 5 an unsightly appearance giving the mistaken impression that the heel is loose and is falling off. These disadvantages are entirely obviated by this improved counter reinforce which may be applied to any boot or 10 shoe at a trifling cost and will promote its increased durability and maintain its neat and attractive appearance at the heel until the shoe is entirely worn out.

I claim as my invention:

- 15 1. In a shoe, the combination with an outer sole, an inner sole and the heel counter and quarter portions having the lower marginal edges turned inwardly, of a reinforcing plate shaped to the dimensions of the interior area of the heel portion of the shoe lying between the outer and inner soles, and devices passing through said parts securing them together before the heel proper is applied.
- 20 2. In a shoe, the combination with the outer and inner soles and the counter and quarter portions lasted with their lower marginal edges turned inwardly, of a re-

inforcing plate having an area corresponding to the desired outline of the interior of the heel portion of the shoe and inserted above the outer sole and the inturned edges of the counter and quarter portions and beneath the inner sole, fastening devices securing said parts together, a heel proper and other fastening devices passing outwardly through the insole, plate and outsole into said heel.

3. A counter reinforce for shoes comprising a substantially flat plate of rigid material having an upwardly projecting flange on its side and rear marginal portions, and adapted to be secured to the outer and inner soles of the heel of a shoe and to reinforce a counter lasted about the same.

4. In a shoe, the combination of inner and outer soles, a counter reinforce of rigid material having an upwardly projecting flange on its outer margin and secured between said inner and outer soles, counter and quarter portions lasted with their edges turned inwardly about the upturned flange of the reinforce, and means for securing the edges of the quarter and counter portions to each other and to the reinforce and inner sole.

LOUIS GOLDSTONE.
